(57) **CLAIM**

What is claimed is the ornamental design for a towel bar, as shown and described.

DESCRIPTION

FIG. 1 is a perspective view of a towel bar showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view.

The components of the display shown in broken lines illustrate portions of the towel bar which form no part of the claimed design.

1 Claim, 4 Drawing Sheets
